UNITED STATES PATENT OFFICE.

FRANK A. ADKINS, OF CHICAGO, ILLINOIS, ASSIGNOR TO CHAMPION FOLDING FURNITURE COMPANY, OF WAUKEGAN, ILLINOIS, A CORPORATION OF ILLINOIS.

FOLDING COT.

Application filed June 15, 1926. Serial No. 116,232.

This invention relates to a folding cot, adapted particularly for camping purposes, so constructed that it will fold compactly and may be readily set up or folded. The 5 frame of the cot, which is made of channeled steel, is strong and durable, and the channeled parts are so connected that when the cot is folded these parts will nest one within the other.

10 The frame of the cot comprises side rails composed of channel bars, each bar consisting of a central section, the channeled side of which faces upwardly when the cot is set up, and two pivotally connected end sections 15 having their channeled sides facing downward, when the cot is set up, and adapted to fold within the central section; legs, composed of channel bars, pivoted to the central section and adapted to fit over the back of said 20 central section when the legs are folded, links for connecting the end section of the side rails to the legs and adapted to fold within the side rails; folding tie rods extending between the legs attached to each side rail and adapted to 25 fold at the sides of the rail and legs, and folding rods at the ends of the cot which connect the legs at the opposite sides of the cot together. The invention also comprises novel 30 means for connecting the mattress frame to the cot frame, comprising hooks on the mattress frame which extend into the channels of the end sections of the side rails and which are readily detached by collapsing the frame.

In the accompanying drawing, 35 Fig. 1 is a top plan view of the cot frame as it appears when set up, the mattress frame being indicated in dotted lines;

Fig. 2 is a side elevation of the cot, set up; Fig. 3 is a central vertical longitudinal section through part of a side bar and leg;

Fig. 4 is an end view of the cot, set up, looking from left to right in Fig. 1;

Fig. 5 is a perspective view of portions of one corner of the cot frame;

45 Fig. 6 is a central vertical longitudinal section through part of a central section of the side bar and through the adjacent end section and leg, showing the same folded; and,

Fig. 7 is a side elevation of part of the 50 side bar, showing a leg and tie rod folded.

Referring to the drawing, *a* and *a'* indicate side rails of the cot, each composed of channel bars and comprising a relatively long central section 1, and end sections 2 which are 55 pivoted to the central section near the ends

of the latter. When the cot is set up, the open sides of the central sections of the side rails face upwardly, and the open sides of the end sections face downwardly, as shown in the several figures of the drawing. The 60 end sections are pivoted at 3, within the central sections, so that the end sections may lie within the central sections when folded, as shown in Fig. 6. The end sections are made wider near their pivoted ends, as indicated at 2^a, so that these end portions will fit closely within the walls of the central sections, to prevent side play, while the remainder of the end sections may be narrower so that they will not frictionally engage the 70 walls of the central sections, thus facilitating folding and unfolding. The parts 2^a of the end sections may be made wider than the remaining parts by cutting out the back of each section and doubling the sides of the 75 channel bar backward to form a double thickness.

The legs 4 of the cot are also composed of channel bars, of slightly greater width than the central sections of the side rails, and each leg has a part of its back portion cut out, leaving forked arms 4^a which fit against the outer side of the central section of the side rail and which are pivoted at 5 to said section, between the end of the section and the 80 pivotal point 3 of the end section 2. The back of the leg between the forked arms abuts against the back of the central section of the side rail, when the cot is unfolded, as shown at 4^b, in Fig. 2. The back thus forms a stop 85 to limit the outward spreading of the leg. The channeled sides of the legs face inwardly when the cot is set up, and when the cot is folded each leg folds around the back and sides of the central section to which it is connected, as shown in Figs. 6 and 7.

Each leg has a longitudinal slot 6 in its back and a pin 7 extends through the side walls of the leg adjacent the slot. Links 8 are pivotally connected at 9 to the end sections of the side rails and are adapted to extend through the slots 6 in the legs. Each link has several notches 10, adapted to engage the pin 7, to lock the end section of the side rail to the leg. The links 8 are pivoted 100 within the channels of the end sections of the side rails about midway of their lengths. The wire fabric or mattress 11 is connected to flat end bars 12, each end bar having hooks 13 which are adapted to extend into the chan- 110

nels of the end sections of the side rails, as shown in Fig. 2. Thus, when the mattress frame is hooked to the end sections of the side rails, after the cot frame has been set up, a downward pressure on the end sections of the side rails will make the mattress taut and the links 8 are then used to lock the end sections to the legs.

The legs on each side of the cot are connected by folding tie rods *t*, each consisting of a relatively long central section 14 and end sections 15, which are pivoted to the central section and also to the pins 7, which extend through the legs. Each leg has a stop 16, pressed out from the outer side of the leg, and this stop prevents the sections 15 of the tie rod from dropping down below the horizontal position when the tie rod is loose, or, in other words, below a line joining the pivotal points 7 of the end sections. These tie rods prevent spreading of the legs longitudinally of the cot. When the cot is folded, the parts 15 of the tie rods fold upwardly alongside of the legs and the central part 14 folds parallel with the parts 15 and the legs and side rails, as shown in Fig. 7.

The legs at opposite sides of the cot frame are connected by folding braces 17 and 18, as shown in Figs. 1, 4 and 5. These braces are pivotally connected together at their centers, as shown at 19, and have downwardly breaking joints 17^a and 18^a. When the braces are folded, the legs to which they are connected are drawn together and the braces extend substantially parallel with the legs.

To fold the cot, the links or latches 8 are released from the pins 7 and this permits the end sections 2 of the side rails to move about their pivotal points. The mattress frame 40 may then be removed by detaching the hooks 13 from the ends of the sections 2, and the latter may be folded within the central section 1, the latching or locking links 8 folding within the side rail, as shown in Fig. 6. 45 The central parts 14 of the tie rods *t* are then moved upwardly and the legs connected by these rods are swung inwardly over the backs of the central sections 1 of the side rails, as shown in Fig. 7. The cross braces 17 and 50 18 are then folded by breaking their joints 17^a and 18^a downwardly, thus bringing the legs and side rails from the opposite sides of the cot together, and the cross braces then lie substantially parallel with the rails and legs. 55 In setting up the cot these operations are reversed, and when the fabric has been connected to the end sections of the side rails, a downward pressure on said end sections will stretch the fabric taut and the links 8 may 60 then be hooked over the pins to hold it taut.

What I claim is:

1. A folding cot comprising side rails and legs composed of channel bars, each side rail comprising a relatively long central sec-

tion and two end sections pivoted within 65 the central section near its ends, said central section having its channeled side facing upward and said end sections having their channeled sides facing downward when the cot is set up, the legs having forked ends pivoted 70 externally to the end portions of the central section and having their channeled sides facing inward when the cot is set up, said end sections adapted to fold within the central sections and the legs adapted to fold over the 75 backs of the central sections, and ties connecting the legs associated with each side rail, each tie comprising a relatively long central section and pivotally connected end sections, the latter pivoted to the legs, said ties adapted 80 to fold parallel with the legs and side rails.

2. A folding cot comprising side rails and legs composed of channel bars, each side rail comprising a relatively long central section and two end sections pivoted within the central section near its ends, said central section having its channeled side facing upward and said end sections having their channeled sides facing downward when the cot is set up, the legs having forked ends pivoted externally 85 to the end portions of the central section and having their channeled sides facing inward when the cot is set up, said end sections adapted to fold within the central sections and the legs adapted to fold over the backs of the central sections, and ties connecting the legs associated with each side rail, each tie comprising a relatively long central section and pivotally connected end sections, the latter pivoted to the legs, and each leg having a projection at one side constituting a stop for 90 limiting the downward movement of the adjacent tie.

3. The combination with a folding cot comprising side rails composed of channel bars, 105 each rail comprising a central section and two pivotally connected end sections, said central section having the channeled side facing upward and said end sections having their channeled sides facing downward when the cot is set up, of a mattress frame comprising end bars having hooks adapted to enter the outer ends of said end sections.

4. A folding cot comprising side rails, channeled legs pivoted to the side rails and adapted to fold around the backs and sides thereof, and leg ties connecting the legs associated with each side rail, each tie comprising a relatively long central section and pivotally connected end sections, the latter pivoted to the 110 legs, and means for preventing the end sections of each tie from dropping below a line joining their points of connection with the legs.

In testimony whereof I hereunto affix my 125 signature.

FRANK A. ADKINS.
